HAIR CURLING DEVICE

Sol Fisher, Cleveland Heights, Ohio

Application March 3, 1939, Serial No. 259,611

4 Claims. (Cl. 132—33)

This invention relates to a method and device for the waving and curling of hair, and particularly to a device and method for producing improved curls in a more efficient and rapid manner.

5 One of the objects of this invention is to provide a device which greatly facilitates the production of soft, flat curls in hair.

Another object is to provide a curling device that can be more easily removed from the entwined hair without destroying the curl.

10 A further object is to provide a method for more rapidly producing curls and waves in hair.

A still further object is to provide a device suitable for making larger and longer curls or waves in hair. Other objects will be apparent from the following detailed description of the method and of the accompanying drawing, in which:

Figure 1 is a perspective view of the curling 20 device;

Fig. 2 is a slightly enlarged sectional view of the device with a curl of hair entwined about the blades and shows the manner in which the hair pin is held in position;

25 Fig. 3 is a plan view of the blade portion of the device; and

Fig. 4 is a cross-sectional view through line 4—4 of Fig. 3 showing the preferred shape of blades.

30 The device comprises a pair of elongated members which cross at a suitable point intermediate their ends in the manner of a pair of shears, and which are connected at their intersection by a suitable pivot 2. These two members are 35 formed to provide, on the one side of the pivot 2, opposed hair gripping blades or arms 3 and 4, and on the other side of the pivot, handle portions 5 and 6, one member forms the gripping arm 3 and handle portion 5, and the other member forms the gripping arm 4 and handle portion 40 6. The entire implement may be made of metal or other suitable material, and the handle portions 5 and 6 may be made of a material different from that of the hair gripping arms 3 and 4 if 45 desired.

The blades 3 and 4 are smooth and have substantial width. They may be made flat and thin but they preferably are formed to an arcuate transverse curvature as shown in Fig. 4. The 50 blades 3 and 4 are preferably so formed that their opposed surfaces will contact substantially throughout their entire extent. Both blades may be of substantially identical form and preferably have uniform thickness over substantially their entire area. The top surface of the blade 4,

which is preferably concave, carries a hair pin holder 7, located centrally of the blade at the outer end thereof which is adapted as shown in Fig. 2 to receive a hair pin or bobby pin 8. In order to facilitate removal of the blades from 5 entwined hair, the pin holder 7 has a sloping inner end 9 which provides a tapering surface which is below the plane of the side edges of the arm 4 at its inner end. A hole 11 is bored through the pin holder 7 substantially parallel to and lengthwise of the blade 4 near the top surface of the blade 4, so that one prong of the hair pin 8, when inserted through the hole 11 will be substantially in contact with the top surface of the blade 4. The vertical distance between the highest point of the top surface of the holder 7 and the center of the hole 11 should be sufficient to cause spreading of the hair pin as 10 shown in Fig. 2.

In order to further facilitate removal of the 20 curling device from a curl of hair the working portion of the blades 3 and 4 are preferably given a slight taper so that their width near the handles and in the vicinity of the shoulder 12 is greater than their width near their unattached 25 or open ends.

In producing curls in hair, a lock of hair is 30 grasped preferably near its end between the blades 3 and 4 and while gripped firmly by means of pressure applied to the handles 5 and 6, it is 35 entwined about or rolled up on the blades 3 and 4 to produce the curl as illustrated in Fig. 2. One prong of a bobby pin or other suitable hair pin is then inserted through the hole 11 in the pin holder 7 where it is held in opened position because of the distance between the hole 11 and the top surface of the holder 7. The operator 40 then grasps the roll or curl of hair entwined about the blades 3 and 4 with one hand and the blades are removed by relieving the pressure between the handles 5 and 6 and withdrawing the gripping arms 3 and 4 by an endwise movement. When the blades 3 and 4 are removed from the curl the hair pin 8 remains in engagement with the curl. The hair pin 8 has a straight prong 45 13 which remains inside the curl and a prong 14 which engages the outside of the curl. Upon removal of the holder 7 the prongs 13 and 14 spring together to firmly grip the curl and hold the same.

The blades 3 and 4 of the curling device, being 50 substantially flat or having an arcuate or other section with a relatively long radius of curvature and being of substantial width, permit the formation of relatively flat soft curls. The tapering 55

blades facilitate the removal of the device from the entwined hair without disarranging the hair in the curl, and the provision of the hair pin applying means greatly lessens the time required for the curling operation. The device is suitable for the production of curls without the necessity for heating, and may be easily withdrawn from a formed curl, whether the hair be wet or dry.

Although a single embodiment of the invention has been herein shown and described it will be understood that numerous modifications of the construction shown may be resorted to without departing from the spirit of this invention as defined in the appended claims.

15. What I claim is:

1. A device for producing relatively flat curls in hair, comprising a pair of similarly shaped relatively wide blades having arcuate transverse curvatures and complementary clamping surfaces, 20 and being pivoted to swing toward and away from each other; a hair pin holder adapted to hold the prongs of a hair pin in an open condition mounted near the unattached end of one of said blades.

2. A device for producing relatively flat curls in hair comprising a pair of relatively wide blades of substantially equal width and having complementary clamping surfaces, said blades being pivoted adjacent one end to swing toward and away from each other and a hairpin holder on 25 the outer face of one of said blades adjacent its outer end, said holder having an aperture adjacent the outer face of the blade to receive one prong of a hairpin and having a body portion of a thickness to engage the opposite prong of

the hairpin and hold the same in open position.

3. A device for producing relatively flat curls in hair comprising a pair of relatively wide blades of substantially equal width and having complementary clamping surfaces, said blades being pivoted adjacent one end to swing toward and away from each other and a hairpin holder on the outer face of one of said blades adjacent its outer end, said holder being in the form of a lug integral with the blade and provided with an 10 aperture adjacent the surface of the blade and extending longitudinally of the blade to receive one prong of a hairpin, said holder having an outer face slanting toward the end of the blade and engageable with the prong opposite that inserted in said aperture to hold the hairpin in 15 open position.

4. A device for producing relatively flat curls in hair comprising a pair of members, each having its opposite end portions formed to provide 20 a handle and a blade and pivotally connected intermediate the blade and handle portions thereof, said blades being of substantially equal width and length, relatively wide and having a slight transverse curvature, said blades being movable into 25 clamping engagement with the convex surface of one bearing upon the concave surface of the other substantially throughout the length thereof, said blades having smooth surfaces and tapering uniformly from their inner to their outer 30 ends, whereby the blades may be readily removed by endwise movement from a curl.
